UNITED STATES PATENT OFFICE

2,102,001

MANUFACTURE OF DRY-SEALING
ENVELOPES

Vincent E. Heywood, Worcester, Mass., assignor
to United States Envelope Company, Springfield, Mass., a corporation of Maine

Application July 16, 1934, Serial No. 735,326

22 Claims. (Cl. 93—61)

The present invention relates to the manufacture of dry-sealing envelopes, that is, envelopes of the type in which corresponding areas of the seal flap and body of each envelope are coated

5 with an adhesive that is adapted to adhere to itself upon contact, without however adhering to the uncoated material of the envelope.

In Conner Patent No. 94,399 dated August 31, 1869, there is shown and described an envelope of the above indicated character, in which is mentioned the necessity of packing such envelopes for use, with the seal flaps turned in to prevent accidental contact of the adhesive coated areas. Bearing in mind the inherent difficulty of turning in the gummed flaps of completed envelopes 15 in the manner suggested in the Conner patent, the present invention contemplates an improved method and means for manufacturing such envelopes, whereby their seal flaps are gummed and folded over upon themselves in advance of converting the envelope material into completed articles.

Furthermore, the present invention contemplates the manufacture of envelopes in the above indicated manner from either a continuous web of material, or separate blanks, with the necessary gumming of the envelope material being carried on continuously to thereby eliminate any tendency for the adhesive to string. Furthermore, the invention provides means for applying printed and coloring matter to the envelope material in process, so that such matter will dry simultaneously with the gumming and before the performance of any folding operations, with further provision of means for reinforcing portions of the envelope material which are subsequently punched out to provide finger holding apertures, such as are provided in merchandising envelopes.

The above and other advantageous features of 40 the invention will hereinafter more fully appear from the following description with reference to the accompanying drawings, in which:—

Fig. 1 is a view in side elevation of the right hand end portion of a machine for carrying out 45 the invention.

Fig. 2 is a view in side elevation of an intermediate portion of the machine.

Fig. 3 is a view in side elevation of the left hand end portion of the machine.

50 Fig. 4 is a plan view of the portion of the machine shown in Fig. 3.

Fig. 5 is a plan view of the portion of the machine shown in Fig. 2.

55 Fig. 6 is a fragmentary sectional view along the line 6—6 of Fig. 1.

Fig. 7 is a vertical sectional view along the line 7—7 of Fig. 2.

Fig. 8 is an enlarged fragmentary view of a portion of Fig. 3.

Fig. 9 is a diagrammatic view in perspective, 5 illustrating the progress of a web of envelope material through the machine and its subsequent conversion into envelopes.

Fig. 10 is a diagrammatic view in perspective, 10 illustrating the progress of envelope blanks through the machine and the manner of gumming the same.

Figs. 11 and 12 are plan views of completed envelopes resulting from the practice of the invention. 15

Like reference characters refer to like parts in the different figures.

Referring to the drawings, the invention will first be described with reference to the manufacture of envelopes from a continuous web of 20 material, and it will hereinafter appear that the mechanism is also capable of handling separate blanks and converting them into envelopes of the same character as those produced from the web. In Fig. 1 a continuous web 1 of envelope 25 material is mounted on a reel 2, from which the web is drawn by rotatably driven rolls 3 and conveyed over the surface of a platen roll 4. A printing roll 5 having suitable characters thereon cooperates with the platen 4 to apply printed 30 matter at spaced intervals to the web 1, as indicated at A in Fig. 9, after which the web is passed around a second platen roll 6. Other printing rolls 7 and 8 cooperating with the platen 6 serve to apply additional printed matter B 35 and C to the web 1 at intervals, preferably in registration with the printed matter A, as shown in Fig. 9.

The web 1 with the printed matter applied at intervals on one side thereof is next led upwardly 40 around a guide roll 9, with which cooperates a fourth printing roll 10 that is adapted to apply a tinted design D to the side of the web opposite to the printing. This tinting is preferably applied in the form of aniline dye which dries very 45 rapidly soon after being applied. The tinted web then passes downwardly around a second guide roll 9a which delivers the web to a horizontally moving belt 11 passing around a cylinder 12. In its travel to the lower guide roll 9a, the web is 50 deflected around the periphery of a gumming roll 13, which as shown in Fig. 6, engages one edge of the web, the other edge of the web being supported by an idler roll 14 mounted on the same shaft 15 as the gumming roll 13. The roll 13 55

rotates in a trough 16 containing adhesive of such a character that when dried, it adheres to any surface coated with the same adhesive, although it will not adhere to the material of the web 1. 5 Preferably, the adhesive in the trough 16 is in the form of a dispersed rubber solution, or as a natural or compounded latex, the invention also contemplating the use of other similar dry-sealing adhesives in the form of thermo-plastics, such 10 as arclor resins or galypols, either alone or in combination with rubber.

The other edge of the web 1 in passing over the idler roll 14 also has adhesive applied thereto by a gumming roll 17 cooperating with the roll 14 15 and engaging the opposite surface of the web. This second gumming roll 17 rotates in a trough 18 containing adhesive of the same character as that contained in the trough 16. Consequently, as the web 1 passes onto the belt 11, it has continuous bands E and F of adhesive extending along its edges on opposite sides thereof, which bands extend beyond the belt 11, as shown in Fig. 7. It will also be noted in Fig. 7 that the printed matter A, B, and C on the web is on the 20 upper side thereof of adjacent the band of gumming E, so that the printed matter is free from engagement with the belt 11 as the web passes into the 25 dryer, the construction of which will be herein-after described.

30 Coincidentally with the gumming of the edges of the web by the rolls 13 and 17, the web has applied thereto patches of reinforcing material located at portions of the web which are subsequently punched through to provide finger openings in the completed envelopes. As best shown in Fig. 6, the patches are adapted to be applied to the same side of the web by rolls 19 and 20 provided around their periphery with spaced projections 21 of frictional material which apply previously gummed patches of predetermined length 35 to the web at intervals corresponding with the spacing of the printed matter on the web. The patch applying rolls 19 and 20 are mounted in spaced relation on the shaft 22, with the roll 19 40 adapted to apply the patches G along an edge of the web corresponding to the edge gumming E by the roll 13 but on the opposite side thereof. The other patch applying roll 20 is mounted adjacent to the gumming roll 17 so that the patches 45 H applied by roll 20 extend in spaced relation on the same side as the band of gumming F, all as indicated clearly in Fig. 4.

The particular mechanism for applying the patches to the web forms no part of the present 55 invention, and a suitable mechanism for carrying out this purpose is shown in Brookes Patent No. 1,338,119 dated April 27, 1920. In Fig. 1 a portion of the patented patch applying mechanism is shown as comprising reels 23 for supplying the 60 patch applying rolls 19 and 20, with the patch material from each reel 23 being operated upon by patch severing and gumming mechanism indicated at 24. Since this mechanism is fully shown and described in the above noted Brookes Patent 65 No. 1,338,119 no further discussion thereof is believed necessary herein, other than to state that rotation of the rolls 19 and 20 causes patches to be severed at intervals from the previously gummed and partially cut webs of patch material, 70 with the gummed sides of the patches being applied to the web 1 at intervals, as indicated at G and H in Fig. 9.

After passing onto the belt 11, the web 1, with the printed matter, the tinted design, the gumming and the reinforcing patches applied thereto, 75

passes through a dryer generally designated by the reference character 25 and extending from the left hand end of Fig. 1 to the right hand end of Fig. 3. As shown in Fig. 7, the dryer 25 provides a long chamber 26 enclosed between a top plate 27 and side walls 28, through which extend heating elements shown in the form of steam pipes 29. The web 1 is supported in its travel through the chamber by guides 30, and the guides 30 are supported at intervals by sets of brackets 10 31 mounted on threaded cross shafts 32. The shafts are oppositely threaded so that by turning the shafts, the guides 30 are adjustable laterally of the chamber 26 to support webs of different widths. An enclosed passage 33 extends through 15 the chamber 26, the top of the passage providing a perforated plate 34 for supporting the belt 11 which is also perforated. The passage 33 is connected to a source of suction, not shown, and the belt 11 traveling through the passage carries with 20 it the web 1 due to the suction effect communicated through the perforations.

When the web 1 emerges from the dryer 25, as shown at the left in Fig. 3, the printed matter and bands of gumming thereon are thoroughly 25 dried and the patches securely fastened to the web. The web then passes upwardly from the dryer 25 around the periphery of a drum 35, which reverses the direction of movement of the web and conveys it for operation upon by a series of cutters 30 which are adapted to convert the web into separate envelope blanks preparatory to the folding operations. As best shown in Fig. 4, a rotatably driven shaft 36 carries cutters 37 and 38 which are adapted to form notches 39 and 40 35 along opposite edges of the web 1. The web then passes between feed rolls 41, after which it is operated upon by a third cutter 42 which is adapted to sever the web at intervals along lines of cutting joining opposed notches 39 and 40. 40 The operation of the cutter 42 therefore serves to divide the web into separate blanks 1a, each having bands of gumming along its edges on opposite sides and with patches and printed matter applied to opposite surfaces of the blank. The 45 cutters 37, 38 and 42 are of the so-called flying shear type and are driven by means of gearing 43 which operates to maintain the cutters in synchronism. The particular manner of driving the cutters forms no part of the present invention, a 50 similar web cutting mechanism being fully shown and described in Sanders Patent No. 1,169,197 dated January 25, 1916.

As each blank 1a is severed from the web 1 by the cutter 42, it passes between cooperating pairs 55 of pull rolls 44 which deliver the blank between cooperating scoring disks 45. As best shown in Fig. 4, these disks 45 serve to score the blank transversely along lines 46a and 46b, with the scoring 46a extending along the margin of the 60 band of gumming F to define the seal flap of the completed envelope. The scoring 46b extends substantially midway of the blank where the width of the blank changes and serves to divide the front wall from the back flap. Since the 65 cutter 42 operates only once for each revolution of the cutter shaft 42a, the blanks are delivered to the rolls 44 at intervals, with adequate spacing between the blanks for proper carrying out of the folding operations which are performed thereon 70 after the scoring, as will next be described.

As best shown in Fig. 3, each scored blank next passes between cooperating belts 47, with which are associated folding instrumentalities, not shown, which serve first to fold the blank along 75

the scoring 46a to turn the small seal flap over with its gummed surface in contact with the body of the blank and then fold the blank along the scoring 46b to turn the larger flap over into engagement with the previously folded seal flap, as indicated diagrammatically in Fig. 4. The particular folding instrumentalities are not shown, since such instrumentalities are well known in the art, as shown for example, in Staude Patent No. 1,144,506 dated June 29, 1915. In the folding over of first the small flap and then the large flap as described above, it is obvious that there is no possibility of the gumming E and F on these flaps coming into contact and therefore adhering to each other, since the small flap which subsequently becomes the seal flap of the completed envelope is folded over to dispose its gumming F face downward against that portion of the blank which subsequently becomes the front wall of the envelope. The gumming F on the seal flap exhibits no tendency to stick to the front wall, since as previously pointed out, the adhesive is of such a character that when dried, it will only adhere to an area gummed with adhesive possessing the same characteristics. The same holds true of the gumming E on the large flap, which while exposed on the portion of the blank which subsequently constitutes the rear wall of the completed envelope, entirely overlies the gumming D and is separated from it by two thicknesses of ungummed paper.

After the folding over of the two flaps as illustrated in Fig. 4, the partially folded blank is delivered by belts 48 against a stop 49, see Fig. 2, for operation upon by another set of instrumentalities shown in the aforesaid Staude Patent No. 1,144,506 which serve to move the blank at right angles to its former movement and at the same time perform scoring, gumming and folding operations thereon which are illustrated diagrammatically in Fig. 5. Since these instrumentalities form no part of the present invention and are well known in the envelope making art, it is believed to be unnecessary to fully show and describe them herein, other than to state the general results accomplished by the operation of these instrumentalities. As a partially folded blank comes to rest against the stop 49, its direction of movement is changed by the conveyor chains 50, as indicated by the arrows in Fig. 5, which deliver the blank to scoring disks 51. These disks 51 score the blank along the lines 52 to define side flaps extending on either side of the body of the blank, and as the blank continues its travel, the side flaps are first gummed at 53 and then folded over to complete the envelope. A finished envelope appears as shown in Fig. 11, with its gummed seal flap turned in and with its rear wall providing a gummed area E corresponding to the concealed gummed area F on the seal flap. Envelopes made in the above described manner are therefore ready to be packed, without any possibility of the dry-sealing adhesive areas E and F coming into engagement. When it is desired to utilize the envelope, it is only necessary to pull out the turned in seal flap, and after the envelope has been folded to turn down the seal flap to bring its gumming F into engagement with the gumming E on the rear wall. The application of pressure alone to the overlying dry-sealing adhesive areas is then all that is necessary to completely seal the envelope.

Previous to the folding over of the side flaps to complete the envelope, the blank is operated upon by a punch 54, which makes an aperture 55 extending through both the front and rear walls of

the envelope and the interposed seal flap. The aperture 55 also extends through the aligned patches G and H on the front and rear walls respectively. In the completed envelope these aligned apertures 55 provide a convenient hand hole for the envelope after it has been closed by pulling out the seal flap and engaging it with the rear wall. Thus, the envelope is rendered extremely useful for carrying articles of merchandise, with the assurance that the articles cannot escape from the envelope after it has been sealed by the application of pressure to the overlying gummed areas E and F.

Referring now to Fig. 9, the progress of the web 1 through the machine is illustrated diagrammatically, so that various operations performed thereon in sequence may be readily understood. Starting from the reel 2, the printed matter A, B, and C is placed upon one side of the web by the successive operations of the printing rolls 5, 7, 20 and 8, as indicated, and as the web starts downwardly toward the gumming and patching instrumentalities, the opposite side of the web from the printing is tinted by the roll 10. In its passage downwardly from the roll 10 the tinting D dries rapidly, as previously pointed out, and the opposite sides of the marginal portions of the web are then gummed, as indicated at E and F. At the same time two series of patches G and H are applied to the tinted side of the web at spaced intervals, following which the gummed, printed and patched web enters the dryer. In its passage through the dryer, the printing and gumming is thoroughly dried, after which the web leaves the dryer and passes upwardly into another plane for operation upon by the cutting instrumentalities.

As designated in Fig. 9, cut #1 results in the formation of the notches 39 and 40, and cut #2 severs the web at intervals between the notches to form completed blanks 1a. The blanks are advanced separately from the cutters and scoring lines are made across each blank as indicated at score #1, preparatory to folding over first the gummed seal flap and then the back flap, as indicated at fold #1 and fold #2. The partially folded blank is then registered and its direction changed at right angles to its previous line of travel, whereupon the scoring defining the side flaps is carried on as indicated at score #2. The side flaps are then gummed and folded to complete the envelope, as indicated at gum #3 and fold #3. Previous to the final folding to complete the envelope, the overlying patches G and H are punched to provide a finger-hole 55 extending through the end of the envelope, it being obvious that the patching and punching may be omitted when it is desired to produce envelopes without finger-holes. Furthermore, it is obvious that the printing and tinting rolls may be omitted when it is desired to produce envelopes having only the self-sealing feature represented by the tucked-in seal flap with its gumming F in overlying relation to the gumming E on the rear wall.

As previously pointed out, the invention also contemplates the manufacture of envelopes from previously cut blanks, and there will next be described the manner in which such blanks may be utilized by the same mechanisms which handle the web 1. Referring again to Fig. 1, a supply of blanks 56 is shown mounted upon a suitable support 57, from which the envelopes are adapted to be removed, one by one, by a suction operated picker 58 of a well known type. The picker 58 is adapted to direct each blank 56

around the periphery of a feed cylinder 59 which cooperates with a roll 60 and a guide 61 to deliver the blanks one by one in a vertical plane to a chute 62. The chute 62 is in turn adapted to 5 deliver blanks to the edge gumming rolls 13 and 17 for the application of dry-sealing adhesive to the margins of the blanks on opposite sides. The speed relation between the gumming rolls 13 and 17 and the feed cylinder 59 is such that the lead- 10 ing edge of one blank arrives at the gumming rolls a little in advance of the trailing edge of the blank that is being gummed, and just prior to the arrival of the leading edge of an un-gummed blank at the gummers, this edge is tucked in behind the trailing edge of the blank being gummed. To this end, a deflector 63 is 15 pivotally mounted adjacent to the chute 62, which is open on the left hand side to permit the deflector 63 to tuck the leading edge of one blank 20 behind the trailing edge of the preceding blanks, as indicated at the right in Fig. 10.

Thus the blanks 56 are disposed in shingled 25 relation, which insures that continuous bands of gumming E' and F' will be applied to opposite edges of the overlapped blanks 56 as they travel into the dryer. The provision of overlapped edges makes it possible to apply the gumming without breaking contact of the rotating gumming elements 13 and 17 with the edges of the 30 blanks. This prevents any tendency for the dry-sealing adhesive to string at the edges of a blank, as would occur were separated blanks engaged by the gumming elements. This provision against 35 stringing of the adhesive is very essential in applying dry-sealing adhesives of the type employed herein, since such adhesives have the property of stringing when moist, which stringiness disappears when such adhesives are thoroughly dry.

40 The shingled blanks 56 gummed along their edges then proceed through the dryer substantially in the form of a continuous web, as clearly shown in Fig. 10, and the functioning of the dryer is such that the gumming E' and F' is thoroughly dry by the time the blanks reach the left hand end of the machine shown in Fig. 3. At this point provision is made for separating the blanks 56 and conveying them upwardly one 45 by one for operation upon by the Staude scoring and folding instrumentalities. The separating and conveying means consists of a pair of conveyor chains 64 passing around sprockets 65, which chains are provided at intervals with lifting fingers 66. As the leading edge of the first 50 blank 56 of a series approaches the chains 64 on the moving belt 11, a deflector 67 directs the blank onto the chains 64. This action is clearly shown in Fig. 8, and as the trailing edge of the first blank approaches the deflector 67, the fingers 66 on opposite sides of the belt 11 engage the trailing edge and serve to separate the blank 55 from the series of shingled blanks on the belt 11. The act of separating is brought about by the fact that the surfaces of the chains 64 travel at a higher lineal speed than the conveyor belt 11. Consequently, the fingers 66 give a distinct push 60 to the trailing edge of the deflected blank which is quite sufficient to break the slight bond between this blank and the adjacent blank due to the bands of gumming E' and F'. The separation of each blank occurs just prior to the engagement of the next succeeding blank by the deflector 67, so that the blanks are conveyed upwardly 65 in a vertical plane by the chain 64 in separated

relation determined by the spacing of the lifting fingers 66 on the chains 64.

As a blank 56 carried by the fingers 66 reaches the top of the conveyor, it is deflected into a horizontal plane by a second deflector 68, so that the blanks are delivered in spaced relation to the pull rolls 44 for operation upon by the scoring rolls 45. From this point on, the operations upon each blank 56 are precisely the same as previously described with reference to the blanks 10 1/2, as cut from the web 1. The progress of the blanks 56 as described in detail above is shown diagrammatically in Fig. 10, from which it is evident that the mechanism of the present invention is adapted to make envelopes as readily from 15 individual blanks as from a continuous web of envelope material.

In Fig. 10 there is also shown a modification in the manner of applying patches I to the blanks 56 when it is desired to make envelopes having 20 finger holes at the closed end thereof, as indicated at 69 in Fig. 12. With this form of envelope, single patches I are applied to the blanks 56 substantially midway of each blank just where the blank is to be subsequently scored and folded, as 25 shown in Fig. 10. However, before folding the blank 56 along scoring 46b, an area of gumming 70 is applied to the blank on the opposite side of the scoring from the patch I, so that when fold 30 #2 is completed, patch I will be solidly adhered to the rear wall of the completed envelope. Then, when the completed envelope is punched to provide the finger hole 69, as shown in Fig. 12, it is 35 evident that the union between the patch I and rear wall will prevent any articles within the envelope from coming out.

I claim:

1. The improvement in the manufacture of envelopes, which consists in providing a blank having 40 separate areas thereof coated with dry-sealing adhesive, next folding the blank to bring one of said adhesive coated areas into engagement with an uncoated area and then folding the remainder of the blank to bring the other adhesive coated 45 area into overlying relation with the first area with its adhesive uppermost in the completed envelope.

2. The improvement in the manufacture of envelopes, which consists in providing a blank having 50 parallel edge areas coated with dry-sealing adhesive, next folding the blank along one edge to cover one adhesive coated area and then folding the remainder of the blank to dispose the adhesive coated areas in overlying relation with the second area uppermost, followed by gumming and folding of other portions of the blank to complete the envelope.

3. The improvement in the manufacture of envelopes, which consists in simultaneously applying 60 continuous bands of dry-sealing adhesive to the opposite sides of moving envelope material, then dividing the envelope material into individual blanks and then folding each blank to bring the bands of dry-sealing adhesive into overlying relation, but facing in opposite directions.

4. The improvement in the manufacture of envelopes, which consists in applying bands of dry-sealing adhesive to the opposed marginal portions of a traveling web of envelope material, then 70 cutting said web into separate blanks and then folding each blank to bring the dry-sealing adhesive bands into overlying relation, but facing in opposite directions.

5. The improvement in the manufacture of en- 75

5 envelopes, which consists in feeding envelope blanks with portions overlapped in shingled relation, simultaneously applying continuous bands of dry-sealing adhesive to opposed marginal portions of the shingled blanks, then separating said blanks and then folding each blank to dispose its dry-sealing adhesive bands in overlying relation, but facing in opposite directions.

6. The improvement in the manufacture of envelopes, which consists in applying bands of dry-sealing adhesive to the opposed marginal portions of a traveling web of envelope material, then cutting said web into separate blanks and then folding each blank to bring the dry-sealing adhesive bands into overlying relation but facing in opposite directions, followed by gumming and folding of other portions of the blank to complete the envelope.

7. The improvement in the manufacture of envelopes, which consists in feeding envelope blanks with portions overlapped in shingled relation, applying continuous bands of dry-sealing adhesive to opposed marginal portions of the shingled blanks, then separating said blanks and then folding each blank to dispose its dry-sealing adhesive bands in overlying relation, but facing in opposite directions, followed by gumming and folding of other portions of the blank to complete the envelope.

8. The improvement in the manufacture of envelopes, which consists in advancing a continuous web of envelope material, applying printed matter to the web, applying bands of dry-sealing adhesive to opposite sides of the web, dividing the web into blanks and then folding each blank into an envelope with the printed matter on the outside and with the bands of dry-sealing adhesive in overlying relation, but facing oppositely.

9. The improvement in the manufacture of envelopes, which consists in advancing a continuous web of envelope material, applying patches of reinforcing material at intervals to the web, applying continuous bands of dry-sealing adhesive to opposite sides of the web, dividing said web into blanks, and then folding each blank into a completed envelope with a patch inside and with the dry-sealing adhesive bands in overlying relation, but facing oppositely.

10. The improvement in the manufacture of envelopes, which consists in advancing a continuous web of envelope material, applying patches of reinforcing material at intervals to the web, applying continuous bands of dry-sealing adhesive to opposite sides of the web, dividing said web into blanks, and then folding each blank into a completed envelope with a patch inside and with the dry-sealing adhesive bands in overlying relation but facing oppositely, followed by the formation of a finger opening in the envelope passing through said patch.

11. The improvement in the manufacture of envelopes, which consists in advancing a continuous web of envelope material, applying patches of reinforcing material at intervals to the web, applying continuous bands of dry-sealing adhesive to opposite sides of the web, dividing said web into blanks, and then folding each blank into a completed envelope with a patch inside and with the dry-sealing adhesive bands in overlying relation but facing oppositely, followed by the formation of a finger opening in the envelope passing through said patch and the overlying adhesive bands.

12. The improvement in the manufacture of envelopes, which consists in advancing a web of

envelope material, tinting one side of said web with a quick drying dye, applying bands of dry-sealing adhesive to opposite sides of said web, severing said web into separate blanks and then folding each blank into an envelope with the tinting inside and with the dry-sealing adhesive bands in overlying relation, but facing oppositely.

13. The improvement in the manufacture of envelopes, which consists in advancing a continuous web of envelope material, applying printed matter to one side thereof, tinting the side of the web opposite from the printing with a quick drying dye, applying bands of dry-sealing adhesive to opposite sides of the web, severing the web into separate blanks and then folding each blank into an envelope, with the printing on the outside, the tinting on the inside, and with the dry-sealing adhesive bands in overlying relation, but facing oppositely.

14. The improvement in the manufacture of dry-sealing envelopes, which consists in feeding envelope blanks from a stack one at a time, overlapping said blanks in shingled relation, simultaneously applying dry-sealing adhesive to opposite sides of said blanks, drying said adhesive separating the individual blanks from said shingled relation, folding the seal flaps and completing the envelopes.

15. The improvement in the manufacture of envelopes, which consists in feeding envelope blanks from a stack one at a time, overlapping said blanks in shingled relation, simultaneously applying continuous bands of dry-sealing adhesive to opposite sides of the continuously moving shingled blank assembly, drying said adhesive and completing the envelopes.

16. The improvement in the manufacture of envelopes, which consists in simultaneously applying dry-sealing adhesive to opposite sides of advancing envelope material, dividing said material into blanks and then folding each blank so that the dry-sealing adhesive areas thereon are out of engagement in a completed envelope made from said blank.

17. The improvement in the manufacture of envelopes, which consists in simultaneously applying dry-sealing adhesive to opposite sides of advancing envelope material, dividing said material into blanks and then folding each blank so that the dry-sealing adhesive areas thereon are separated by a non-adhesive portion of the blank in a completed envelope.

18. The improvement in the manufacture of envelopes, which consists in simultaneously applying dry-sealing adhesive to opposite sides of envelope material, dividing said material into blanks and then folding each blank so that the dry-sealing adhesive areas thereon are disposed in overlying relation in a completed envelope, with a non-adhesive portion of said blank disposed between said adhesive areas.

19. The improvement in the manufacture of envelopes, which consists in providing a blank having parallel edge areas coated with dry-sealing adhesive, next folding the blank along one edge to cover one dry-sealing adhesive area, and then gumming and folding the remainder of the blank to complete the envelope and to cause said dry-sealing adhesive areas to face in opposite directions in overlying relation, with the other dry-sealing adhesive area uppermost.

20. The improvement in the manufacture of envelopes, which consists in applying bands of dry-sealing adhesive to opposed marginal portions of a traveling web of envelope material, then cut-

ting said web into separate blanks and gumming and folding over portions of each blank to complete an envelope, with the bands of dry-sealing adhesive in overlying relation, but facing in opposite directions in the completed envelope.

21. A step in the manufacture of an envelope having corresponding areas of its seal flap and rear wall coated with dry-sealing adhesive, which consists in folding over that portion of an envelope blank which later constitutes the seal flap to cover the dry-sealing adhesive thereon, in advance of any other folding operations on the envelope blank.

22. A step in the manufacture of an envelope having corresponding areas of its seal flap and rear wall coated with dry-sealing adhesive, which consists in folding over that portion of an envelope blank which later constitutes the seal flap 5 to engage the dry-sealing adhesive thereon with that portion of the blank which later constitutes the front wall of the envelope, in advance of folding the remainder of the envelope blank to dispose the rear wall adhesive area over the folded 10 seal flap, but facing oppositely thereto.
